[57] CLAIM

The ornamental design for a compact disc novelty plaque, as shown and described.

DESCRIPTION

FIG. 1 is a front elevational view of a compact disk novelty plaque showing my new design, the broken-line showing of a CD, a CD insert, and label are for illustrative purposes only;

FIG. 2 is a right-side elevational view thereof, the left side being a mirror image;

FIG. 3 is a top plan view thereof, the bottom being a mirror image;

FIG. 4 is a rear elevational view thereof; and,

FIG. 5 is a cross-sectional view thereof, taken in the direction of the arrows along line 5—5 of FIG. 1.
